(57) CLAIM

The ornamental design for a slidable cosmetic container, as shown and described.

DESCRIPTION

FIG. 1 is a perspective view of a slidable cosmetic container; FIG. 2 is a front elevation view of the slidable cosmetic container of FIG. 1;

FIG. 3 is a back elevation view of the slidable cosmetic container of FIG. 1;

FIG. 4 is a right-side elevation view of the slidable cosmetic container of FIG. 1, the left-side elevation view being a mirror image of the right-side elevation view;

FIG. 5 is a top plan view of the slidable cosmetic container of FIG. 1; and,

FIG. 6 is a bottom plan view of the slidable cosmetic container of FIG. 1.

The broken lines form no part of the claimed design. The claimed design extends to the broken line boundary in FIG. 6, but does not include the boundary or the area within the boundary.
